(57) **CLAIM**

The ornamental design for forestry forwarder cab, as substantially shown and described.

DESCRIPTION

FIG. 1 is a first side view of a forestry forwarder cab showing our new design;

FIG. 2 is a second side view thereof;

FIG. 3 is a back view thereof;

FIG. 4 is a front view thereof; and,

FIG. 5 is a top view thereof.

The broken line showing of the wheels in FIGS. 1 and 2 is included for the purpose of illustrating portions of the forestry forwarder cab forming no part of the claimed design.

1 Claim, 5 Drawing Sheets

FIG. 1

FIG. 2

FIG. 3

FIG. 4

FIG. 5
